UNITED STATES PATENT OFFICE.

CHARLES GREGORY, OF DENISON, TEXAS, ASSIGNOR OF ONE-HALF TO WILLIAM FREEMAN, OF DENISON, TEXAS.

BOOT AND SHOE STRETCHER.

Application filed May 8, 1925. Serial No. 28,931.

This invention relates to a boot or shoe stretcher, the primary object of the invention being to provide a stretcher of this character so constructed that it may be employed 5 for use in stretching boots or shoes of various sizes, eliminating any possibility of breaking the counter of the boot or shoe in the application of the device.

Another object of the invention is to provide a device of this character wherein the stretching member forming a part thereof, is interchangeable, thereby providing a stretcher possessing unlimited adjustments.

A still further object of the invention is 15 the provision of a stretcher so constructed that it may be positioned or removed from a boot or shoe with facility.

With the foregoing and other objects in view which will appear as the description 20 proceeds, the invention resides in the combination and arrangement of parts and in the details of construction hereinafter described and claimed, it being understood that changes in the precise embodiment of the invention herein disclosed, may be made within 25 the scope of what is claimed, without departing from the spirit of the invention.

Referring to the drawings:

Figure 1 is a plan view of a boot or shoe 30 structure constructed in accordance with the invention.

Figure 2 is a sectional view taken on line 2—2 of Figure 1.

Figure 3 is a sectional view taken on line 35 3—3 of Figure 2.

Figure 4 is an elevational view of the operating member.

Figure 5 is a vertical sectional view taken 40 through the central portion of the expanding member as shown by Figure 8.

Figure 6 is an elevational view of the pivoted heel section forming a part of the invention.

Figure 7 is a sectional view taken on line 45 7—7 of Figure 2.

Figure 8 is a side elevational view of an expanding member.

Figure 9 is a side elevational view of the main expanding section.

50 Referring to the drawings in detail, the reference character 5 indicates the body portion of the stretcher which is relatively long and hollow, the same being provided with an angularly disposed end portion 6. Extending laterally from the end portion are arms

7 providing bearings for the sectional last-like expanding member 8 to be hereinafter more fully described.

This expanding member 8 embodies sections 9 and 10 respectively, which sections 60 are formed with openings 11 extending transversely therethrough and which accommodate the arms 7, the openings 11 being slightly larger than the arms 7 to permit a 65 rocking movement of the sections 9 and 10 with respect to the arms.

Formed in the arms 7 are suitable vertical openings that are adapted to register with openings formed in sections 9 and 10, which registering openings accommodate the 70 screws 12, whereby the sections 9 and 10 are removably supported on the arms 7 to the end that sections of various sizes may be employed in connection with arms 7.

The inner edges of sections 9 and 10 are 75 formed with grooves 14, the inner surfaces of which grooves being curved as at 15, and clearly shown in Figure 1 of the drawings.

Cooperating with the curved surfaces 15 is an expanding head 16, which is also 80 formed with outer curved edges indicated at 17, which bear against the curved surfaces 15 to the end that when the expanding head 16 moves towards the outer end of the member 8, the sections 9 and 10 are moved outwardly away from each other to accomplish 85 the stretching action for which the device is designed.

Formed integral with the head is a rearwardly extended portion 18 formed with a 90 bore 19 to accommodate one end of the flexible member 20, which flexible member extends into the body portion 5 where it has connection with the inner end of the screw 21, the end of the flexible member 20 being 95 shown as secured within an opening 20' formed in the inner end of the screw 21.

This screw 21 is formed with a handle 22 there being provided a pin 23 extending through the handle to secure the handle to 100 the flexible member 20. The screw 21 operates through the threaded cap 24 which is screwed onto the supporting section 5 so that as the screw 21 is rotated, it may move into 105 and out of the supporting section according to the direction of rotation of the screw.

In order that the inward movement of screw 21 will act on the head 16 to move it outwardly, a plurality of blocks 25 are positioned on the flexible member 20 which 110

blocks engage the inner surface of the hollow bar 5 to prevent rotation of the flexible member when the handle 12 is rotated to the end that as the screw 21 moves into contact with block 25 disposed adjacent thereto, the blocks will be moved along with the flexible member 20, moving the head 16 accordingly, and as head 16 moves to the outer end of the grooves 14, handle 22 will engage the cap 10 24 and prevent further movement of the member 20.

Thus it will be seen that due to this construction, the head 16 will be held within the confines of the grooves at all times, eliminating any possibility of the head 16 passing beyond the outer end of the expanding member 8. It will also be obvious that as the screw 21 is reversed, the inner edges of the head 16 will engage the shoulders at the 20 bases of the grooves 14 and restrict further movement of the head, to prevent undue strain being directed to the flexible member 20.

The heel section of the stretcher includes a 25 body portion 27 which is formed with an opening to accommodate the threaded shank 28 formed with an offset portion 29 which is pivotally connected with the ears 30 formed integral with the body portion 5 so that as 30 the heel portion 27 moves downwardly, the offset portion 29 will engage the body portion 5 to resist downward movement of the heel member 27.

Supported at the rear of the expanding member is a spring 31 formed with a looped portion 32 the ends thereof being secured to the sections of the expanding member by means of staples 33 so that the spring will normally act to urge the sections 9 and 10 40 of the expanding member towards each other, with the result that when the head 16 is moved to its normal position within the

expanding member, the sections 9 and 10 will move under the action of the spring to their normal or closed positions.

45

Associated with the expanding member are auxiliary expanding members 34 that are provided with pins 35 adapted to be positioned in suitable openings formed in the outer surfaces of the sections 9 and 10 to 50 removably support the members 34. The member 34 is also formed with openings to accommodate the pin 36 provided on the removable stretching members 37 to the end that a pocket may be formed in a shoe to 55 accommodate a corn on the foot of the wearer of the shoe stretcher by the device.

These members 37 may be of various formations and to this end openings 38 are provided in the outer curved surfaces of the 60 member 34 to accommodate pins carried by interchangeable stretching members 37.

I claim:—

In a stretcher of the class described, a hollow body portion, an expanding member including pivoted sections connected with the hollow body portion and having grooves formed in the inner surfaces thereof, a movable expanding member operating within the grooves, a flexible member in the form 70 of a wire extending through the hollow body portion and having connection with the expanding member, a plurality of oblong blocks slidably mounted on the flexible member, said blocks adapted to engage the inner 75 surface of the hollow body portion to prevent rotation of the flexible member, and means at one end of the flexible member for moving the movable expanding member between sections of the expanding member.

In testimony that I claim the foregoing as my own, I have hereto affixed my signature.

CHARLES GREGORY.
